CHUCK

Donald J. McCarthy, Wethersfield, Conn., assignor to The Jacobs Manufacturing Company, West Hartford, Conn., a corporation of New Jersey

Filed Nov. 25, 1966, Ser. No. 4,803

Term of patent 14 years

U.S. Cl. D54—14
Int. Cl. D15—05

FIG. 1 is an elevational view of a chuck embodying my new design;

FIG. 2 is a bottom end view thereof;

FIG. 3 is a view reverse to that of FIG. 1, showing the opposite area of the chuck;

FIG. 4 is a top end view of the chuck;

FIG. 5 is an elevational view of a modified form of a chuck embodying my new design;

FIG. 6 is a bottom end view thereof;

FIG. 7 is a view reverse to that of FIG. 5 showing the opposite area of the chuck; and

FIG. 8 is a top end view thereof.

I claim:

The ornamental design for a chuck, substantially as shown and described.
